UNITED STATES PATENT OFFICE.

WILLIAM H. MINER AND JOHN F. O'CONNOR, OF CHICAGO, ILLINOIS, ASSIGNEES, BY
MESNE ASSIGNMENTS, TO WILLIAM H. MINER, OF CHICAGO, ILLINOIS.

TANDEM-SPRING DRAFT-RIGGING FOR RAILWAY-CARS.

1,136,030.

Specification of Letters Patent. Patented Apr. 20, 1915.

Application filed April 19, 1909. Serial No. 490,828.

To all whom it may concern:

Be it known that we, WILLIAM H. MINER and JOHN F. O'CONNOR, citizens of the United States, residing in Chicago, in the county of Cook and State of Illinois, have invented a new and useful Improvement in Tandem-Spring Draft-Rigging for Railway-Cars, of which the following is a specification.

10 Our invention relates to tandem spring draft rigging for railway cars.

The object of our invention is to provide a tandem spring draft rigging of a strong, simple, efficient and durable construction, 15 and in which the side plates or stop castings shall be anchored to and combined with the car framework in a very firm, safe and secure manner.

Our invention consists in the means we 20 employ and herein shown and described for practically accomplishing this result, as more particularly set forth in the claims.

In the accompanying drawing forming a part of this specification, Figure 1 is a side elevation partly in central vertical section, 25 of a tandem spring draft rigging embodying our invention. Fig. 2 is a plan view partly in horizontal section. Figs. 3, 4 and 5 are vertical cross sections on the lines 3—3, 30 4—4 and 5—5 respectively of Fig. 2. Fig. 6 is a detail plan view of one of the tie-plates. Fig. 7 is a detail perspective view of one of the side plates or stop castings.

In the drawing, A A represent the center 35 sills or draft timbers or other longitudinal frame members of the car to which the draft rigging is directly applied, A¹ the front or end sill, A² the buffer block and A³ is a transversely extending abutment or 40 member of the car frame at the rear of the draft rigging.

B is the draw-bar and B¹ the draw-bar strap or yoke secured to the draw-bar by rivets b and interengaging lugs or shoulders b¹ b² on the draw-bar. The draw-bar strap is furnished with a middle abutment block b³ having curved faces b⁴ to engage the middle followers and secured in place by rivets b⁵. At its rear end the draw-bar yoke B¹ is furnished with a curved loop b⁶ and a semi-cylindric filler block b⁷ to abut against the rear follower, and which is secured in place by a rivet b⁸.

C, C¹ are tandem arranged springs be- 55 tween the followers E E¹ E² E³.

D D are the side plates or stop castings furnished with stops or shoulders d d¹ d² d³ for the followers to abut against, and intermediate stops or shoulders d⁴ d⁵ d⁶ d⁷ to limit the compression of the springs by engagement with the followers. Each of the side plates or stop castings D has a forward outwardly inclined extension d⁸ extending to the extreme front end of the car framework where it is provided with a lateral flange d⁹ flush with the upright front face of the abutment block A². Each of the side plates or stop castings D is also furnished with an integral rearward extension d¹⁰ having a right angle foot or flange d¹¹ abutting against a shoulder a on the rear transverse frame or abutment member A³. Each of the side plates or stop castings D is also provided with upper and lower outwardly extending flanges d¹² and d¹³, thus giving the side plate 75 or stop casting a general channel form in cross section, while its inner face is left free from upper and lower flanges and substantially straight or smooth, excepting for the jogs, convolutions or bends which form the 80 several stops and intermediate stops.

To afford an additional anchorage of the side plates or stop castings to the car frame, each of the side plates or stop castings D is furnished with an integral upwardly projecting abutment d¹⁴ which fits against the front end of the longitudinal car frame sill or member A and in a suitable notch or recess a¹ in the end or front sill A¹.

The upper horizontal flange d¹² of the outwardly flanged or channel shaped stop casting D fits under and abuts against the lower horizontal face of the car frame members A A¹ and is secured thereto and to the buffer block A² by vertical bolts F. 90

G G are also removable guides secured to the side plates or stop castings D by bolts g and upon which the followers rest and reciprocate.

H H are tie plates extending between and 100 secured to the side plates or stop castings D. These tie plates H are secured in place by bolts h extending through the horizontal flange d¹³ of the side casting. Each of these tie plates H is furnished with a central longitudinal guide or channel h¹ for the lower member of the draw-bar strap or yoke B¹ to fit and reciprocate in, and is provided at its outer ends with seats h² to receive the lower horizontal flanges d¹³ of 105 110

the channel shaped stop castings D and with shoulders h^3 for the outer edges of said flanges d^{13} to abut against. The tie plates H are secured to the lower horizontal flanges d^{13} of the stop castings D by removable bolts h having threaded nuts h^5 and keys h^6 .

The longitudinal frame members A A of the car to which the side plates or stop castings D are secured are placed closer together than the length of the followers so that the ends of the followers will project under these longitudinal frame members of the car and render unnecessary any upper guide flange for the followers on the side plates or stop castings D, thus materially simplifying their construction.

H^1 H^2 are rear upper and lower reinforcement plates extending between and firmly secured to the upper and lower flanges d^{12} d^{13} of the stop castings D by rivets h^7 . And H^3 H^4 are front upper tie plates secured to the upper flanges d^{12} of the stop castings D by rivets h^7 , the tie plate H^4 having an upright integral flange H^5 .

H^6 is the front carry iron supported by the bolts h^8 .

The inner upright faces of the stop castings D, it will be seen from Fig. 7 of the drawing, are substantially straight and smooth except for the upright recesses D^1 therein to receive the ends of the followers. And, as will be seen from Fig. 2, these recesses D^1 and the stop shoulders d^1 d^2 d^3 d^4 d^5 d^6 and d^7 are formed by simple bends in the main upright web D^3 of the stop casting. This gives the stop casting an exceedingly simple, strong and effective form free from projections or flanges on its inner face and of a substantially channel form in cross section at all parts of its length.

We claim:—

1. In a tandem spring draft rigging, the combination with the draw-bar, draw-bar yoke, tandem arranged springs and followers, of outwardly turned, channel shaped stop castings, each furnished with transverse bends in the main, upright web thereof of forming stops for the followers to abut against, said web being also provided with further transverse bends forming intermediate stops for the followers to abut against to limit the compression of the springs, the vertical faces of all the bent out portions of the web and of the intervening portions

between the bent out portions being flat and unbroken, and the upright recesses intervening between the stops extending entirely across the stop casting from the upper to the lower face thereof and adapted to receive the followers, the castings being secured to the under sides of the draft sills of the car by bolts extending through the upper flanges only of the castings, substantially as specified.

2. As an article of manufacture, a stop casting for railway draft rigging, the said stop casting comprising a channel-shaped member, the flanges of which are arranged to be turned outwardly when applied in position, said channel-shaped member being furnished with transverse bends in the main upright web thereof forming stops for the followers to abut against with intervening upright recesses extending across said member from the upper to the lower face thereof, said recesses being arranged to receive the followers, and the flanges of said channel-shaped member being entirely to one side of the main web thereof and the stop portions to the other side of the main web, substantially as specified.

3. As an article of manufacture, a stop casting for railway draft riggings which comprises a channel-shaped member, the flanges of which are arranged to be turned outwardly when said member is applied in position, said member being furnished with transverse bends in the main upright web thereof forming stops for the followers to abut against with intervening upright recesses extending across said member from the upper to the lower faces thereof, said recesses being adapted to receive the followers, the flanges of said member being located entirely to one side of the main web and the stop portions to the other side of the main web, said member being provided with a forward extension having a laterally extending flange adapted to lie flush with the front face of the car-frame work, said member being also provided with a rearward extension adapted to abut against the transverse member of the car-frame at the rear of the draft rigging, substantially as specified.

WILLIAM H. MINER.
JOHN F. O'CONNOR.
